[57] CLAIM

The ornamental design for a console for teleconferencing communication, as shown.

DESCRIPTION

FIG. 1 is a left side, top and front end perspective view of a console for teleconference communication showing our new design;

FIG. 2 is an enlarged top plan view thereof;

FIG. 3 is a front end elevational view;

FIG. 4 is a right side elevational view;

FIG. 5 is a rear end elevational view;

FIG. 6 is a left side, top and front end perspective view of a second embodiment thereof, with all other views appearing substantially as in FIGS. 3, 4 and 5.

FIG. 1

FIG. 2

FIG. 3

FIG. 4

FIG. 5

FIG. 6
